MUSIC LEAF TURNER

Filed Dec. 17, 1923

2 Sheets-Sheet 2

UNITED STATES PATENT OFFICE.

ALBERT B. WOECKENER, OF ROCK ISLAND, ILLINOIS.

MUSIC-LEAF TURNER.

Application filed December 17, 1923. Serial No. 681,241.

To all whom it may concern:

Be it known that I, ALBERT B. WOECKENER, a citizen of the United States, residing at Rock Island, in the county of Rock Island and State of Illinois, have invented certain new and useful Improvements in Music-Leaf Turners; and I do declare the following to be a full, clear, and exact description of the invention, such as will enable others skilled in the art to which it appertains to make and use the same.

The principal object of my invention is to provide a music leaf turner by the use of which, a plurality of holders for leaves of music may be successively carried from retaining means on a music rack or stand, to receiving means on said rack or stand, and turned during their movement from the one position to the other, the construction being such that the musician's hands are free for use upon his instrument.

Other objects are to provide the retaining means, the receiving means, the sheet holders and their carrying means, and all other parts, in simple yet effective and durable forms.

A still further object is to provide for easily attaching the turning means to and detaching it from the music stand or rack.

With the foregoing in view, the invention resides in the novel subject matter hereinafter described and claimed, the description being supplemented by the accompanying drawings.

Figure 1 is a perspective view of a music stand equipped with the invention.

Figure 2 is a front elevation of the sheet-turning means.

Figure 3 is an upper edge view with the sheet carrier in the same position as disclosed in Fig. 2.

Figure 4 is a view similar to Fig. 3, but illustrating the leaf carrier approaching the receiving means and about to release the sheet holder which it is carrying from the retaining means.

Figure 5 is a view similar to Fig. 4 but illustrating the sheet holder released from the carrier and engaged with the receiving means.

Figure 6 is a longitudinal sectional view as indicated by line 6—6 of Fig. 2.

Figure 7 is a longitudinal section on line 7—7 of Fig. 6.

Figures 8 and 9 are vertical transverse sectional views on lines 8—8 and 9—9 of Fig. 2.

Figure 10 is a plan view of one of the sheet holders.

Figure 11 is a sectional perspective view showing the gripping means with which the carrier is provided, to engage the sheet holders.

Briefly described, the invention comprises retaining means R for a plurality of music sheet holders H, receiving means R' to successively receive the holders H, a sheet carrier C having gripping means G for gripping the holders H successively and bodily carrying them into engagement with the receiving means R', and releasing means for said gripping means. These numerous elements of the invention may take form in numerous ways, but the construction specifically described below is preferable. Also, although I have shown the invention in connection with a music rack r of a music stand S, it will be understood that it may be used in connection with other forms of racks or supports for the sheets of music to be turned.

In the construction disclosed, an elongated bar 1 has been shown, carrying the music-turning means and provided at its ends with hooks 2 for passage around the ends of the rack r, the upper edge of said bar 1 being provided with projecting fingers 3 which may be pivotally mounted if desired, said fingers being adapted to abut the upper edge of the rack and hold the bar 1 against downward sliding. This mounting of the bar 1 permits it to be readily attached to the rack or detached therefrom, as occasion may require.

The retaining means R has been shown as consisting of pairs of pins 4 and 5 extending forwardly from the right-hand end of the bar 1, while the receiving means R' has been shown as consisting of a pair of curved pins 6 in the same plane with the pins 4, said pins 6 being projected from the other end of the bar 1.

The holders H for the sheets of music have been shown in the form of elongated plates having suitable clips 7 for attaching them to the upper edges of the sheets, each holder being formed with a pair of openings 8 to first receive the pins 4 as shown in

Figs. 1, 2 and 3 but to later receive the pins 6, as disclosed in Fig. 5. I have shown the upper edge of each holding plate provided with an upstanding flange 9 which 5 is clinched at 10 around the intermediate portion of a length of wire, the ends 11 of this wire being extended beyond the flange 9, so as to provide each of the sheet holders with a pair of gripping pins. One pin of 10 each holder is intended to be gripped by the gripping means G and it will be seen that providing each holder with a pair of these pins 11, makes such holder reversible so that it cannot be erroneously applied. Attention 15 may here be directed to the fact that the pins 5, above referred to, loosely engage the upper portions of the flange 9 and assist in retaining the holders H in proper position.

The carrier C is by preference in the form 20 of a pivoted arm including inner and outer sections 12 and 13 which are relatively movable. In the construction shown (see Figs. 6 and 7), the inner arm section 12 is formed with a longitudinal guide slot 14 in which 25 the outer section 13 is slidably received, a coiled spring 15 being housed within said section 12 to normally project the section 13. This last named section carries the gripping means G and is preferably in the form of 30 a flat spring, as shown.

The arm section 12 has been illustrated, as being detachably mounted upon a suitable bracket 16 which is in turn detachably connected at 17 with a block 18 at the center 35 of the bar 1. The pivoted end of this arm section is provided with a pulley portion 19 with which a suitable spring 19' is associated to normally throw the carrier C toward the right, to the position shown in 40 Figs. 1, 2 and 3. An operating cable 20 however is engaged with the pulley 19, passes through notches 21 in the parts 18 and 1, and is trained around a suitable guide sheave 22 carried by said part 18. The 45 lower end of the cable 20 is secured to a suitable foot pedal 23 connected with the stand S in any desired manner, so that by depressing this pedal, the carrier C will be swung to the position disclosed in Fig. 5, 50 while release of said pedal, will permit the carrier to return to its original position, as disclosed for instance in Fig. 1.

The gripping means G, in the construction shown, includes a housing 24 carried 55 by the outer end of the arm section 13, said housing having a throat 25 to receive the pins 11 of the holders H. Within the housing 24, a pair of gripping jaws 26 have been shown, said jaws having notches 27 in their inner edges to grip the pins 11. I have 60 shown the housing 24 as formed with open sides at the outer edges of the jaws 26 and have illustrated a U-shaped spring 28 straddling the housing with its arms disposed at 65 said open sides and engaged with the jaws

26, so as to yieldably force these jaws inwardly toward each other, yet to allow them to separate whenever the throat 25 receives one of the pins 11.

When the holders H are engaged with 70 the receiving means R', the outer section 13 of the carrier C is slid inwardly as disclosed in Fig. 5, whereby to withdraw the gripping means G from the pin 11 previously held, so as to leave the holder engaged with 75 said receiving means and permit the carrier C to return to the stack of holders in the retaining means R to grip the next holder. To slide the section 13 in this manner, I have shown an arm 29 pivoted to the arm section 12 and connected by a flexible connection 30 with the outer arm section 13, said connection 30 being by preference engaged 80 with a suitable guide sheave 31 on the arm section 12. I have shown the arm 29 provided with a lateral projection 32 and in the path of this projection, a stationary stop 33 is provided on the bar 1. Thus, about 85 the time the sheet holder H is engaged with the receiving means R', the projection 32 strikes the stop 33 as disclosed in Figs. 4 and 5, thus causing a swinging of the arm 29, a consequent pull upon the connection 30, and inward sliding of the arm section 13, so that the gripping means G is withdrawn 90 from the pin 11 previously held thereby.

Projection of the arm section 13 to an excessive extent, is prevented by a lateral finger 34 on an auxiliary arm 35 which extends 100 from the arm section 12, along the arm section 13. This same finger prevents movement of the holder H with the outer section 13, as the latter starts toward the arm section 12, as will be seen by reference to Fig. 4. Also, 105 by referring to Fig. 2, it will be seen that the finger 34 acts as a feeler to strike the foremost of the holders H held by the retaining means R, so as to relatively position the gripping means and the holder, incident to engagement of the one with the other.

The operation of the device is as follows: The sheets of music to be turned, are provided with the holders H and the latter have their openings 8 passed over the pins 4, so 115 that a stack of them is held by these pins. The carrier C which has been held in a forward position, is now released and its spring 19' moves it to the right, so that the jaws 26 grip the foremost of the pins 11. When now, 120 the pedal 23 is depressed, the carrier C is swung to the left causing the gripping means G to carry with it, the foremost of the holders H. If the pedal 23 is depressed to the maximum, the carrier C swings entirely over 125 to the left and the holder is deposited upon the pins 6, the gripping means being released from the pin 11, by movement of the arm 29, when it encounters the stop 33. If the 130 pedal is not entirely depressed, it will be

seen that the carrier C may be stopped in the position disclosed in Fig. 4 and consequently the holder H may be returned to the retaining means R, if this should be necessary, for instance, to again play the notes on one side of the sheet held by said holder.

A device constructed as, or substantially as shown and described, has proven to be highly efficient and desirable and as excellent results are obtainable from the present disclosure, the details shown may well be followed. However, it will be understood that within the scope of the invention as claimed, the device may be embodied in a great number of forms.

I claim:

1. A music leaf turner comprising a rack, means on said rack for loosely retaining a stack of sheet holders, additional means on said rack for successively receiving the holders as the sheets are turned, a leaf carrier mounted for movement from said retaining means to said receiving means and including means for gripping the foremost of the stack of sheet holders and bodily carrying the same to said receiving means, and means for automatically releasing said gripping means.

2. A music leaf turner comprising a rack, pins projecting forwardly from one end thereof for loosely retaining a stack of sheet holders, additional pins extending forwardly from said rack for successively receiving the sheet holders as the sheets are turned, a leaf carrier mounted for movement from said retaining pins to said receiving pins and including means for gripping the foremost of the stack of sheet holders and bodily carrying the same to said receiving pins, and means for automatically releasing said gripping means.

3. A music leaf turner comprising a plurality of sheet holders adapted to be connected with the edges of sheets of music, each of said holders having a projecting pin, a rack for supporting the sheets, said rack having means for loosely retaining a stack of said holders, means on said rack for successively receiving said holders as the sheets are turned, a sheet carrier movable from said retaining means to said receiving means and including means for gripping the projecting pin of the foremost sheet holder and bodily carrying the latter to said receiving means, and means for releasing said gripping means.

4. A music leaf turner comprising a plurality of sheet holders adapted to be connected with the edges of sheets of music, each of said holders having a projecting pin, a rack for supporting the sheets, said rack having means for loosely retaining a stack of said holders, means on said rack for successively receiving said holders as the sheets are turned, a sheet carrier movable from said retaining means to said receiving means and

including means for gripping the projecting pin of the foremost sheet holder and bodily carrying the latter to said receiving means, and means for automatically sliding said gripping means from the pin held thereby when the holder is in engagement with said receiving means.

5. A music leaf turner comprising a plurality of sheet holders adapted to be connected with the edges of sheets of music, each of said holders having a projecting pin, a rack for supporting the sheets, said rack having means for loosely retaining a stack of said holders, means on said rack for successively receiving said holders as the sheets are turned, a sheet carrier movable from said retaining means to said receiving means and formed of inner and outer movably connected sections, the outer section having means for gripping the projecting pin of the foremost sheet holder and bodily carrying the latter to said receiving means, and means for relatively moving said sections of said carrier to slide said gripping means from the pin held thereby when the holder is engaged with said receiving means.

6. A music leaf turner comprising a plurality of sheet holders adapted to be connected with the edges of sheets of music, each of said holders having a projecting pin, a rack for supporting the sheets, said rack having means for loosely retaining a stack of said holders, means on said rack for successively receiving said holders as the sheets are turned, a sheet carrier movable from said retaining means to said receiving means and formed of an inner section and an outer spring projected section slidably connected therewith, said outer section having means for gripping the projecting pin of the foremost sheet holder and bodily carrying the latter to said receiving means, and means for automatically sliding said outer section inwardly with regard to the inner section to slide said gripping means from the pin held thereby when the holder is in engagement with said receiving means.

7. A music leaf turner comprising a plurality of sheet holders adapted to be connected with the edges of sheets of music, each of said holders having a projecting pin, a rack for supporting the sheets, said rack having means for loosely retaining a stack of said holders, means on said rack for successively receiving said holders as the sheets are turned, a sheet carrier movable from said retaining means to said receiving means and formed of an inner section having a guideway and an outer resilient section slidably engaged with said guideway, said outer section having means for gripping the projecting pin of the foremost sheet holder and bodily carrying the latter to said receiving means, and means for automatically sliding

4
said outer section inwardly with regard to the inner section to slide said gripping means from the pin held thereby when the holder is in engagement with said receiving means.

8. A music leaf turner comprising a plurality of sheet holders adapted to be connected with the edges of sheets of music, each of said holders having a projecting pin, 10 a rack for supporting the sheets, said rack having means for loosely retaining a stack of said holders, means on said rack for successively receiving said holders as the sheets are turned, a sheet carrier movable from 15 said retaining means to said receiving means and formed of inner and outer movably connected sections, the outer section having means for gripping the projecting pin of the foremost sheet holder and bodily carrying 20 the latter to said receiving means, a movable member mounted on said inner section and having a connection with said outer section for inwardly moving the latter, and a stationary stop on the rack in the path of said 25 movable member to actuate the latter and slide said gripping means from the pin held thereby when the holder is in engagement with said receiving means.

9. A music leaf turner comprising a plurality of sheet holders adapted to be connected with the edges of sheets of music, each of said holders having a projecting pin, a rack for supporting the sheets, said rack having means for loosely retaining a stack 30 of said holders, means on said rack for successively receiving said holders as the sheets are turned, a sheet carrier movable from said retaining means to said receiving means and formed of an inner section and an outer 35 spring projected section slidably connected therewith, said outer section having means for gripping the projecting pin of the foremost sheet holder and bodily carrying the latter to said receiving means, an arm pivoted to said inner section and having a connection with said outer section for sliding the latter inwardly, and a stationary stop on the rack in the path of said arm to actuate the latter and slide said gripping means 40 from the pin held thereby when the holder is in engagement with said receiving means.

10. A structure as specified in claim 3; together with a feeler on said sheet carrier for relatively positioning said gripping means and the projecting pin of said foremost sheet holder incident to engagement of the one with the other.

11. A structure as specified in claim 6; together with combined means on said inner 60 section of said sheet carrier for limiting the outward projection of said outer section and for relatively positioning said gripping means and the projecting pin of said fore-

most sheet holder incident to engagement of the one with the other.

12. A music leaf turner comprising a plurality of sheet holders adapted to be connected with the edges of sheets of music, each of said holders having a projecting pin, a rack for supporting the sheets, said rack having means for loosely retaining a stack of said holders, means on said rack for successively receiving said holders as the sheets are turned, an arm pivoted on said rack to swing from said retaining means to said receiving means, said arm being formed of an inner and an outer section slidably connected with each other and means for yieldably projecting the outer section, said outer section having means for gripping the projecting pin of the foremost of said holders and bodily carrying the latter to said receiving means, means for automatically sliding said outer arm section inwardly to disengage said gripping means from the pin held thereby when the sheet holder of such pin is engaged with said receiving means, and an auxiliary arm secured to said inner arm section and extending along the outer arm section, said auxiliary arm having a lateral finger at its outer end for limiting the projection of said outer arm section, said finger being also adapted to strike the foremost of the sheet holders and relatively position the same and said gripping means incident to engagement.

13. A structure as specified in claim 3; said gripping means comprising a housing on said carrier having a throat to receive the projecting pin of the foremost sheet holder, and relatively movable spring-closed pin-gripping jaws mounted in said housing at opposite sides of said throat.

14. A structure as specified in claim 3; said gripping means comprising a housing on said carrier having a throat to receive the projecting pin of the foremost sheet holder, relatively movable pin-gripping jaws mounted in said housing at opposite sides of said throat, said housing having open sides at the outer portions of said jaws, and an arched spring straddling said housing and having its ends disposed at said open sides thereof and engaged with said jaws.

15. A sheet holder of the class described comprising a plate for connection with the sheet, said plate having a projecting flange centrally between the ends thereof, and in the same plane as the plate and a length of wire around whose intermediate portion said flange is clinched, the ends of the wire being extended beyond the ends of the flange to provide projecting pins.

In testimony whereof I have hereunto affixed my signature.

ALBERT B. WOECKENER.
